UNITED STATES PATENT OFFICE.

LAWRENCE RICHARDSON, OF LOUISVILLE, KENTUCKY.

FEEDING DEVICE FOR LOCOMOTIVE TENDERS.

1,426,675.

Specification of Letters Patent. Patented Aug. 22, 1922.

Application filed July 13, 1920. Serial No. 395,992.

To all whom it may concern:

Be it known that I, LAWRENCE RICHARDSON, citizen of the United States of America, residing at Louisville, in the county of 5 Jefferson, and State of Kentucky, have invented certain new and useful Improvements in Feeding Devices for Locomotive Tenders, of which the following is a specification.

The invention relates to improvements in 10 a locomotive tender coal pit.

It has been proposed in the prior art to provide a locomotive tender coal pit adapted to feed coal by gravity to a shovel space, which gravity feed is augmented by the vibration of the tender. These constructions 15 have been used to prevent coal, when the same becomes moist, from accumulating in back of the tender with the idea of always insuring a supply of coal in a space accessible 20 to the fireman. These structures have been recognized by those skilled in the art as being decidedly troublesome and objectionable inasmuch as the vibration of the tender is not sufficient to cause an ample supply 25 of coal to be fed to the shovel pit at all times, especially where the coal is in a decidedly moist condition and little or no material vibration is encountered.

It is an object of the present invention to 30 provide a locomotive tender coal pit with means for positively feeding coal, regardless of its condition, to a shovel pit from which it is removed and introduced to the locomotive firebox. In carrying out the invention, a positive means of driving power 35 is employed for feeding the coal over the sloping wall of the pit and into a relatively wide coalpocket extending transversely of the tender and lying in a plane below the 40 sloping wall.

It is a further object of the invention to provide a construction in which the feed wall of the tender is perforated near one end to permit fine coal to pass therethrough when 45 being moved over the inclined wall and deposit at the rear of the shovel pit, while the larger particles of coal are carried over the inclined wall by the positive feed to the forward part of the pit. This is highly desirable 50 inasmuch as it enables the finer coal to be segregated from the coarser lumps. It is appreciated by those skilled in this art that where the fine coal is scattered promiscuously within the furnace, the draft has a 55 tendency to carry these particles in suspen-

sion through the stack where they are lost. It will therefore be seen that the present construction enables the coarser coal separated from the fine slack to be deposited by the fireman in the locomotive firebox at the desired point while the finer particles collected in the rear portion of the coal pocket may be placed in the rear portion of the fire box so as to prevent the same from being discharged through the stack in a green condition.

The invention further comprehends a locomotive tender pit, wherein the feeding conveyor is driven by a power device, preferably using compressed air or steam from the locomotive as a source of power supply, and under the instant control of the operator, so that the desired quantities of coal can be fed to the shovel pit from time to time as the occasion may require, irrespective of the vibration of the tender or the condition of the coal contained therein.

In the accompanying drawings I have shown a specific embodiment of the invention for the purpose of illustration, but it will of course be understood that this disclosure is subject to many modifications without departing from the spirit of the invention.

In the drawings, Figure 1 is a detail longitudinal vertical section of the tender, 85 partly in elevation showing the feeding device and shovelling space.

Figure 2 is a detail plan view showing the coal-advancing means.

Referring now more particularly to the drawings, the reference numeral 1 designates the body of a locomotive tender which is of the conventional type having the usual wheels, the rear portion of the tender constituting a water reservoir, while the forward portion thereof is adapted to receive coal or a like fuel. The forward portion of the tender is provided with an inclined surface 2, terminating near one end in a right angular extension 3 from which a relatively 95 straight portion 4 projects to the forward part of the tender.

Spaced from the surface 2 is the inclined or sloping wall 5, which extends from a point beyond the upper surface 2 of the tender 105 1, to a point in advance of the portion 3 of the tender and constitutes a bed upon which the coal in the tender rests. At each end of the bed are journaled suitable sprockets 7 and 8, receiving chains 9, to 110

which are attached suitable conveyors 10 disposed between the chains and extending entirely across the wall or bed 5. The conveyors are moved in the direction of the arrow shown in Figure 1, through the medium of a motor 11, preferably driven by compressed air or the like, and of any convenient type. Air is introduced to the motor through the feed pipe 12 leading from the engine or other suitable source of supply and is controlled by the hand manipulated valve 13 which is located at a point accessible to an operator so that the conveyor or may be placed in operation whenever desired.

It will be understood that much difficulty has heretofore been experienced in the use of locomotive tenders due to the fact that when the supply of coal becomes rather low, or the coal is thoroughly saturated with water, the same will not freely feed down the inclined wall to a shovel pit. The coal has a tendency to adhere to the surface of the wall and pack in a relatively solid mass which has been the source of much labor and trouble to locomotive firemen. This coal at times becomes exceedingly hard, and requires much force to move the same.

The present invention aims to provide a positive means for feeding the coal over the wall down into the undercut shovel pit 14 located beneath the wall 5 and constituting a coal receiving pocket which is of a relatively large capacity and from where the coal is removed by the firemen to be deposited in the engine. This coal is positively fed upon the actuation of the conveyor passing downwardly over the inclined surface 5, and when coal is passed over the lower portion of this surface, the exceedingly fine particles drop through the apertures 15 disposed within that portion of the surface extending above the coal pocket 14 so that the fine coal is collected in the rear portion of the pocket. The larger coal of course is carried by the conveyor beyond the forward end of the surface 5 and is there deposited within the coal pocket 14 so that the coal is not only fed by the construction disclosed in the present invention, but is also classified and the finer particles separated from the coarser particles. This is highly desirable inasmuch as when fine particles of coal are indiscriminately thrown into a furnace a great deal of the fine coal is entrained and carried away by the drafts passing out through the locomotive stack, especially where such fine coal is deposited in the fire box at a point of high draft. In the present invention, the fireman is permitted to remove the larger particles of coal and place them where desired in the firebox, after which he is enabled to get the fine coal which may be used for bank-

ing the fire, or may be deposited in the rear portion of the fire box where the air draft is not very heavy.

When in operation the conveyor is placed in actuation by the manipulation of the hand lever 13 and coal is continuously fed to the relatively long coal pocket existing substantially the entire distance across the tender. This operation of the conveyor is continued until the coal pocket is filled, whereupon the hand lever 13 is actuated to discontinue the operation of the conveyor. When the supply in the coal pocket begins to diminish it is, of course only necessary to acuate the hand lever to feed an additional supply of coal to the pocket and it will be appreciated that when following this invention, the coal pocket is always maintained sufficiently full of coal regardless of the wet or moist condition thereof, or the vibration of the tender which experience has demonstrated is not sufficient to efficiently feed coal to the pocket under all conditions.

In the accompanying drawings I have disclosed the conveyor as to be operated by an air motor, but it will be appreciated that other sources of power may be employed wherever found desirable, and that the type of conveyor herein described is subject to many changes and modifications.

Having thus described my invention, what I claim is:

1. A locomotive tender shovel pit having an inclined feeding surface, and a shovel pit at one end thereof disposed below the inclined surface and from which coal is manually removed, and means adjacent said feeding surface for positively feeding coal over the surface into the shovel pit.

2. A locomotive tender coal pit having a coal supporting surface, a shovel pit at the forward end of said surface disposed below the coal supporting surface and accessible to permit coal to be manually removed therefrom, and mechanical means adjacent said surface for positively feeding coal to the shovel pit.

3. A locomotive tender coal pit having a coal supporting wall, and an undercut shovel pit at the forward end thereof, a conveyor for feeding coal over said wall to said undercut shovel pit, and power means for actuating said conveyor.

4. A locomotive tender coal pit having an inclined wall upon which coal is supported, and an undercut shovel pit disposed beneath said wall, a conveyor passing over the wall, and means for positively operating said conveyor to feed coal to said shovel pit.

5. A locomotive tender coal pit having an inclined coal surface and an undercut shovel space extending below said surface, said surface projecting over a portion of the shovel space and having an aperture there-

- in for the passage of fine particles of coal therethrough into the shovel space, while larger particles of the coal pass over said surface and around the end thereof into the 5 shovel pit.
6. A locomotive tender coal pit having an inclined coal surface and an undercut shovel space extending below said surface, said surface projecting over a portion of the 10 shovel space and having an aperture therein for the passage of fine particles of coal therethrough into the shovel space, while larger particles of the coal pass over said surface and around the end thereof into the 15 shovel pit, in combination with means for positively feeding said coal to the shovel pit.
7. A locomotive tender coal pit having a coal supporting wall and an undercut shovel pit at the forward end thereof, and means 20 for feeding coal over said wall to said undercut shovel pit.
8. A locomotive tender coal pit having an inclined wall upon which coal is supported and an undercut shovel pit disposed beneath 25 said wall, mechanical means adjacent said wall for feeding coal thereover to the shovel pit, and a power device for actuating said mechanical means.
9. A locomotive tender adapted to receive
- a supply of coal and having a shovel pit at 30 one end thereof accessible from the tender apron permitting the coal to be manually transferred from said shovel pit, and means movable relative to the tender for augmenting the gravity feed of the coal from the 35 tender to the shovel pit.
10. A locomotive tender adapted to receive a supply of coal and having a shovel pit at one end thereof accessible from the 40 tender apron permitting the coal to be manually transferred from said shovel pit, movable means for positively shifting the coal from said tender to the pit and a power device for actuating said means.
11. A locomotive tender pit having a coal 45 supporting surface and an undercut shovel space below said surface at one end thereof, said surface projecting over a portion of said shovel space and having an aperture therein for the passage of fine particles of 50 coal passing over said surface into the shovel pit, while larger particles of coal are caused to pass beyond the opening and around the end of said surface into the shovel pit.

In testimony whereof I affix my signature. 55

LAWRENCE RICHARDSON.
